CLAIM

The ornamental design for a sandal upper, as shown and described.

DESCRIPTION

FIG. 1 is a perspective view of the sandal upper;

FIG. 2 is another perspective view of the sandal upper;

FIG. 3 is a back perspective view of the sandal upper;

FIG. 4 is a top view of the sandal upper;

FIG. 5 is a side view of the sandal upper;

FIG. 6 is another side view of the sandal upper;

FIG. 7 is a front view of the sandal upper; and,

FIG. 8 is a rear view of the sandal upper.

The broken line showing of sole of the sandal is included for the purpose of illustrating environment and forms no part of the claimed design.
